UNITED STATES PATENT OFFICE

WALTER EVERETT MOLINS AND GEORGE DANIEL HORGAN, OF DEPTFORD, LONDON, ENGLAND

MACHINE FOR PACKING CIGARETTES

Application filed May 1, 1931, Serial No. 534,412, and in Great Britain May 6, 1930.

This invention relates to machines for packing cigarettes and has for its object to provide means whereby oval cigarettes may be arranged in lapped formation ready for insertion into a carton or the like. The invention is also useful for completely turning over cigarettes for a purpose hereinafter described.

The invention consists of an apparatus for arranging oval cigarettes in lapped formation, comprising means for delivering a row of cigarettes to a table with their major axes parallel to the same, means for conveying the cigarettes through guides arranged to rotate or tilt the cigarettes so that their major axes lie at substantially the same angle to the table, and means for moving the tilted cigarettes towards one another so as to obtain the required lapped formation.

The invention will be more particularly described with reference to the accompanying drawings, in which:—

Fig. 1 is a section of a portion of a cigarette packing machine with the invention applied thereto.

25. Fig. 2 is a plan of Fig. 1.
 Fig. 3 is a section of Fig. 1 on line 3—3.
 Fig. 4 is a section of Fig. 1 on line 4—4.
 Fig. 5 is a perspective view of a detail.
 Fig. 6 is an end view of another detail.
 30. Fig. 7 is a perspective view of a modification.

Referring to the drawings, the cigarettes are fed from a hopper (not shown) into vertical slots 1 formed by a group of vanes 2 and delivered to a plate or table 3 on which they are spaced apart sufficiently to permit them to lie flat.

A conveyor 4 having pusher pieces 5 carries the row of cigarettes through a set of 40 slots 6 formed by turning guides 7.

At the entry, each slot is sufficiently wide to permit the cigarettes to lie flat upon the plate 3 whilst at the exit the slot is considerably narrower, the cigarettes being turned in transit so that they will pass through the narrow outlet.

The turning guides 7 are shaped as shown in Fig. 5, and as each cigarette passes through the slots 6 it is turned through an angle by 50 the ledge or rib 8 engaging with one side

thereof, and pressing this side downwards, and when the cigarettes emerge from the slots 6 they are all standing on the plate 3 at an acute angle thereto.

The shape of the guides as shown in Fig. 5 ensures that all the cigarettes rotate through the same angle and in the same direction, and yet are prevented from rising bodily from the plate 3 as the rib 8 causes one side of the cigarette to be held down whilst the other side rises as the slot 6 becomes narrow.

In order to correctly guide the cigarettes into the slots 6, the table 3 is preferably provided with a series of curved grooves 9 in which the cigarettes move shortly after they fall from the vane slots, and they are guided into the grooves and spaced correctly by a series of fingers 10 formed in a block 10^a suspended above the table and pressed downwardly by a spring 11. The fingers also guide the cigarettes into the slots 6; a section of several of the fingers is shown in Fig. 6.

The guides 7 are carried in a frame pivoted at 12 so that it may be easily lifted should a jam occur. The frame is free to move upwards in the slots at the pivots so that the conveyor bar which pushes the cigarettes can pass beneath the guides 7.

After the cigarettes pass through the slots 6 they are delivered into a tapering guide 80 channel 13, the width of which is sub-divided by small guides 14.

In the case illustrated only five cigarettes are being fed and two pass at each side in the space 15 whilst the fifth one passes in the 85 central space 16.

When larger numbers of cigarettes are being fed, a sufficient number of the guides 14 are furnished so that every pair of cigarettes is separated by a guide similar to 14. 90 As the cigarettes emerge from the channel 13 they are all correctly lapped as required, as the space 17 between the guides is sufficiently narrow to prevent the cigarettes from lying flat and as they are all tilted to the same 95 angle and in the same direction they naturally fall upon one another in the manner required.

In the machine illustrated, provision is made for superimposing two or more rows 100

upon one another, and this is effected by delivering the rows in succession into the guide space 17 from which they are removed by a pusher piece 18 carried on another conveyor 5 19.

In order to ensure that the layers are not disturbed during this movement a cam operated plate 20 is arranged to receive each layer and press the same downwardly 10 between the guides.

A light curved spring 21 on the end of the plate 20 facilitates this action by resting on the leading ends of the cigarettes as they are being delivered into position on the bed.

15 Although the invention has been described forlapping cigarettes, it is obvious that by extending the guides 7 and curving them suitably any one of the cigarettes may be turned through such an angle that it will eventually fall over when free of the vanes so that it lies on its reverse side. In Fig. 7 a single guide 22 suitable for this purpose is shown.

This method of completely reversing the cigarettes is of use when the cigarettes are to 25 be automatically packed with the printed inscription on the upper surface and any cigarette which is initially lying with the inscription on its lower surface may be turned over by interposing in its path a guide such 30 as 22, the guide being operated by any suitable mechanism which is in turn actuated from an apparatus which detects whether the cigarette is lying the right side up or not.

The detecting apparatus forms no part of 35 the present invention, but such detecting apparatus usually consists of light-sensitive cells which control electro-magnets through relays. In the present case each guide 22 would be raised and lowered by a separate 40 magnet.

What we claim as our invention and desire to secure by Letters Patent is:—

1. In apparatus for arranging oval cigarettes in lapped formation, the combination 45 with means for moving a batch of cigarettes in the direction of their length with the major axes thereof substantially horizontal, guide means through which the cigarettes are moved for engaging the same to tilt the 50 major axes, and converging guides through which the tilted cigarettes are moved for compacting the cigarettes to obtain the desired lapped formation.

2. In apparatus for arranging oval cigarettes in lapped formation, the combination 55 with means for moving a batch of cigarettes in the direction of their length with the major axes thereof substantially horizontal, and laterally disposed guides having a spacing less than the major axis of the cigarette 60 through which the cigarettes are moved, each guide being cut away at the entrance portion thereof to provide a cam shoulder for engaging and depressing one side of the cigarette 65 to tilt the same.

3. In apparatus for arranging oval cigarettes in lapped formation, the combination with means for moving a batch of cigarettes in the direction of their length with the major axes thereof substantially horizontal, 70 of guide means through which the cigarettes are moved for engaging the same to tilt the major axes, converging guides through which the tilted cigarettes are moved for compacting the cigarettes to obtain the desired lapped formation, a bed on which the lapped cigarettes are discharged, and means for engaging a batch of the discharged cigarettes to retain the same in lapped relation 75 while the succeeding batch is discharged thereon in superimposed relation.

4. In apparatus for arranging oval cigarettes in lapped formation, the combination with means for moving a batch of cigarettes in the direction of their length with the major axes thereof substantially horizontal, of guide means through which the cigarettes are moved for engaging the same to tilt the major axes, said guide means being movable 80 vertically to permit passage of said first named means thereunder.

5. In apparatus for arranging oval cigarettes in lapped formation, the combination with means for moving a batch of cigarettes in the direction of their length with the major axes thereof substantially horizontal, of guide means through which the cigarettes are moved for engaging the same to tilt the major axes, and a bed located in advance of 90 said guide means and provided with grooves extending in the direction of the length of the cigarettes, said grooves conforming in cross-sectional area to the shape of the broad sides of the cigarettes to locate the cigarettes with their major axes disposed substantially horizontal.

6. In apparatus for arranging oval cigarettes in lapped formation, the combination with means for moving a batch of cigarettes in the direction of their length with the major axes thereof substantially horizontal, of guide means through which the cigarettes are moved for engaging the same to tilt the major axes, a bed located in advance of said 110 guide means and provided with grooves extending in the direction of the length of the cigarettes, said grooves conforming in cross-sectional area to the shape of the broad sides of the cigarettes to locate the cigarettes with their major axes disposed substantially horizontal, and yielding means engaging the cigarettes to guide the same into the said 115 grooves.

In testimony whereof we hereunto affix our 120 signatures.

WALTER EVERETT MOLINS.
GEORGE DANIEL HORGAN.
